PROCESS FOR HYDROCARBON CONVERSION

Karl H. Hachmuth, Bartlesville, Okla., assignor
to Phillips Petroleum Company, a corporation
of Delaware

Application October 3, 1942, Serial No. 460,703

17 Claims. (Cl. 260—683.5)

This invention relates to the removal of metal halides, especially active metal halides of the Friedel-Crafts type, from admixture with hydrocarbons. More particularly it relates to the removal of such metal halides as aluminum chloride and the like from solution or suspension in substantially saturated hydrocarbons. It has particular applicability to non-destructive hydrocarbon conversions utilizing Friedel-Crafts type metal halide catalysts, wherein traces of such catalyst are carried over in the saturated hydrocarbon effluents.

Of great commercial interest at the present time are the isomerization and alkylation of low-boiling hydrocarbons, particularly members of the paraffin series such as the butanes and pentanes. In these reactions, a simple chemical change is effected under relatively mild conditions. In the case of isomerization, a change in carbon skeleton without change in number of carbon atoms occurs, and in the case of alkylation, the direct union of two molecules, such as an isoparaffin and an olefin, occurs to produce a higher molecular weight saturated hydrocarbon. These reactions are known to be catalyzed in a greater or lesser extent by the so-called Friedel-Crafts catalysts, among the better known of which may be mentioned aluminum chloride, aluminum bromide, boron fluoride, zinc chloride, ferric chloride, antimony trifluoride, and other polyvalent metal halides. Aluminum chloride has as to date received the greatest commercial acceptance due to its activity, relatively low cost, and availability. Accordingly, because of its importance, and for the sake of convenience I shall describe my invention with particular reference to the isomerization of normal butane to isobutane as catalyzed by aluminum chloride. Application of the invention to other similar hydrocarbon conversions, using aluminum chloride or other Friedel-Crafts type metal halide catalysts, in which substantially saturated hydrocarbon effluents are produced, will be apparent to those skilled in the art in view of the detailed disclosure to follow.

Aluminum chloride and other Friedel-Crafts catalysts are relatively volatile, and may also exhibit appreciable solubility in liquid hydrocarbons. This volatility and solubility give rise to serious operating difficulties, particularly in continuous processes. The isomerization of butane may be carried out with the hydrocarbon in the liquid or gaseous phase, the latter being more often used. Small but appreciable quantities of aluminum chloride are carried out of the

catalyst chamber along with the isomerization products. This aluminum chloride is deposited in the transfer lines, valves, and other parts of the equipment, particularly at points of lower temperature than that obtaining in the catalyst chamber. These deposits of aluminum chloride require frequent shut down to enable their removal, with consequent loss of plant capacity and the expenditure of otherwise unnecessary labor. The corrosive effects of the aluminum chloride are also frequently serious, particularly in the valves and pumps. It is also difficult to obtain products of the process free from aluminum chloride, which may interfere with subsequent use of such products.

It is an object of this invention to provide for the removal of active metal halides from admixture with hydrocarbons. A further object is to provide improvements in the non-destructive conversion of relatively low-boiling hydrocarbons with Friedel-Crafts type metal halide catalysts. A further object is to remove from saturated hydrocarbon effluents from the catalyst zone the volatilized and/or dissolved metal halide catalyst contained therein, and thus avoid fouling of equipment through which such effluents subsequently pass. A further object is to provide a method of freeing substantially saturated hydrocarbons from aluminum chloride vaporized, dissolved, and/or suspended therein. Many other objects as well as advantages of this invention will be apparent from the present disclosure.

I have found that free aluminum chloride or other similar metal halide may be removed from admixture with substantially saturated hydrocarbons by reacting unsaturated hydrocarbons, such as monoolefins, diolefins, acetylenes, etc., with said metal halide to form a metal halide-hydrocarbon sludge which is readily separable as a separate phase from either gaseous or liquid saturated hydrocarbons. According to my invention, I incorporate said metal halide in such a sludge, and separate the saturated hydrocarbons from the sludge. The metal halide may be incorporated in the sludge in the free state, or in the combined metal halide-hydrocarbon sludge form, but in either case the metal halide is reacted with unsaturated hydrocarbons prior to, during, or after its incorporation into said sludge. It is preferable that sufficient unsaturates be provided to free such sludge from uncombined metal halide, or at least to reduce the concentration below the level at which it is objectionable in subsequent processing.

Olefins or other unsaturates utilized in this

invention act to sludge the aluminum chloride or other metal halide, and a portion of the olefins may also frequently react to form olefinic polymers, or if the saturated hydrocarbons undergoing treatment contain alkylatable hydrocarbons, may react with the same to give alkylation products. Such higher molecular weight hydrocarbons so formed comprising polymers and/or alkylate, may be recovered as valuable products and utilized in aviation gasoline blends or otherwise as desired.

The amount of unsaturates required is ordinarily very small as compared with the volume of hydrocarbons being treated. Frequently less than one per cent of unsaturates is sufficient, and more than a few per cent is seldom necessary. In some cases a considerable excess of unsaturates may be used, and the unreacted portion thereof subsequently recovered if desired. Such recovery may be from the saturated hydrocarbons by fractionation or the like, or in certain methods of operating, to be described in detail below, the unsaturates are not mixed directly with the saturates, and any excess is thus more readily recovered.

My invention is especially applicable to isomerization of low-boiling saturated hydrocarbons such as normal butane, normal pentane, normal hexane, etc. to form the corresponding isoparaffins. It is also quite applicable to the 30 alkylation of alkylatable hydrocarbons, especially the relatively low-boiling isoparaffins, with alkylating agents, low-boiling olefins such as propylene, butylenes, and pentenes being ordinarily used. In such an alkylation although olefins are present in the reaction zone proper, the reaction zone effluent or alkylate is often substantially saturated, and appreciable quantities of the metal halide catalyst are to be found dissolved or suspended in the effluent. The catalyst may be used in the reaction zone either as a solid or as a slurry comprising considerable amounts of metal halide dissolved and/or suspended in liquid hydrocarbons or other suitable liquids. The carried-over metal halide may appear in the reaction zone effluents in the vaporized form or dissolved or suspended in liquid effluents.

Temperature and pressure conditions used in the hydrocarbon conversions referred to are mild 50 so that no extensive decomposition reactions occur, the exact conditions being readily chosen by one skilled in the art for the particular isomerization, alkylation, or other reaction involved. In most cases the temperatures in the sludge-forming zone will be similar to those in the reaction zone, but may be appreciably lower.

Metal halide-hydrocarbon sludge formed in carrying out my invention may be sent to sludge disposal, to a process for recovery of metal halide therefrom, or to other use as desired.

The accompanying drawing and description thereof are provided for the purpose of better illustrating and exemplifying the invention, and show different ways of applying the invention to a butane isomerization process. Numerous other modifications may be used, for carrying out various reactions, by following the teachings of this disclosure, and no particular limitations are therefore implied. Figure 1 shows in diagrammatic form one suitable arrangement of apparatus, and Figure 2 shows another suitable arrangement of apparatus wherein one or more sludge-contacting chambers may be used, with the un- 70

75 saturated hydrocarbons being admitted to the process either intermittently or continuously.

Referring now to Figure 1, dry gaseous normal butane, either pure or containing minor amounts of isobutane and/or lighter gases such as propane, along with activating amounts of anhydrous hydrogen chloride or other activating agent, is introduced into the bottom of catalyst chamber 1A through conduit 2A. The hydrogen chloride may be introduced into the reaction zone in other ways if desired, and in most cases will comprise from 3 to 15 mol per cent of the feed. Chamber 1A is operated at a pressure of 100 to 150 pounds per square inch gage and a temperature of about 200° F. The feed being introduced through conduit 2A is heated to the proper temperature by means not shown. If necessary, the butane is dehydrated before introduction to the catalyst. The flow rate will generally be between about 0.1 to 2.0 liquid volumes of hydrocarbon feed per volume of catalyst chamber per hour. Catalyst chamber 1A contains pieces of solid anhydrous aluminum chloride of about 20 mesh or larger, or may contain suitable supported aluminum chloride catalysts known to the art.

The gaseous effluent from chamber 1A which comprises isobutane, normal butane, hydrogen chloride, lighter gases, and small amounts of volatilized aluminum chloride, leaves the top of chamber 1A via conduit 3. Spent aluminum chloride, which usually forms as a sludge, may be removed from chamber 1A either continuously or intermittently through conduit 4.

35 Unsaturated hydrocarbons, for example propylene or butylenes or a mixture containing the same, are injected into admixture with the gases in conduit 3, as through line 5. These unsaturated hydrocarbons react rapidly with the aluminum chloride vapors in the reaction zone effluent to form an aluminum chloride-hydrocarbon sludge containing substantially no free or uncombined aluminum chloride. At least sufficient unsaturates are provided to effect substantially complete removal of the aluminum chloride as sludge. If an excess is added, it may later be removed from the isomerization products by fractionation or other suitable means if desired. A portion of the olefins may alkylate some of the isobutane, and the small amount of heavier isoparaffins thus formed may be subsequently separated from the butane.

The material in line 3 passes into separator 6 where the insoluble sludge drops out from the gases and is removed via conduit 7. The isomerization effluents thus freed of sludge and aluminum chloride pass out from separator 6 to further treatment, separation, or the like via conduit 8. If desired, separator 6 may be filled with any suitable type of packing to aid in collecting and separating the sludge from the hydrocarbon stream, such as rocks, Raschig rings, or the like. In case the conversion in chamber 1A is carried out in the liquid phase, residual catalyst carried out by solution in the hydrocarbon liquids reacts with the added unsaturated hydrocarbons to form a sludge which is insoluble in the liquid hydrocarbons, and thus readily separated in unit 6 as a phase separate from the hydrocarbons.

The effluents from separator 6 comprise unconverted normal butane, isobutane produced in the process, traces of five-carbon-atom and heavier hydrocarbons, hydrogen chloride, and minor amounts of other gases lighter than isobutane

which may have been introduced into the feed and/or produced by side reactions.

Hydrogen, and sometimes propane, may be used in the butane isomerization process to minimize undesired side reactions and maintain catalyst life. The amount of propane used may be as high as ten per cent or more, while much smaller volumes of hydrogen are usually used. It will be understood that the effluent from the process as just described may be subjected to any of the separating or other steps known to the art. These usually include separation of hydrogen chloride, propane, and unconverted normal butane, which are recycled to catalyst chamber 1A. Various other expedients which are known to the art may of course be utilized as particular circumstances indicate.

The effluents in line 8, due to the action of the added olefins, are substantially free from residual aluminum chloride, which makes possible their further treatment without encountering the troublesome condensation of aluminum chloride in lines and equipment as discussed hereinabove.

In Figure 2, the butane feed enters catalyst chamber 1A, which contains the aluminum chloride catalyst, through conduit 2A, and conversion products, including small amounts of aluminum chloride, exit through line 3. Line 4 is provided for removing any sludge which accumulates in chamber 1A. Two contacting chambers, 9 and 10, are shown in Figure 2. These chambers are packed with ceramic rings or other suitable contact material to promote intimate contact between hydrocarbons and sludge. Other devices adapted to achieve this contact may of course be used, but I have found this particular type of chamber to be especially advantageous.

In one modification of my invention, only one such chamber is used. In this case, the effluents in conduit 3 are passed via line 11 into the bottom of chamber 9. Unsaturated hydrocarbons are passed from conduit 5 either into line 11 via line 13 as shown or directly into chamber 9, for reaction with the aluminum chloride carried over from catalyst chamber 1A. Sludge formed by the action of the olefins or other unsaturates on the aluminum chloride separates out onto the packing in chamber 9. This sludge runs down over the packing, presenting a highly extended surface to the hydrocarbons, and is removed from the bottom of chamber 9 through line 15. It is recycled via line 17 by pumping, pressuring, or other means, and introduced into the top of chamber 9, wherein it again flows down over the packing. Excess sludge is drawn off through line 1A. Isomerization effluents free from aluminum chloride leave chamber 9 via conduits 19 and 21, and pass to separation means indicated diagrammatically at 32, wherein the product, in this case isobutane, is separated and recovered via line 33, while unconverted material, such as normal butane, and catalyst promoter, such as HCl, are recycled to the catalyst chamber via lines 34, 35 and 36.

The sludge on the packing in chamber 9 may have a dual function. It aids in separating from the hydrocarbons additional sludge formed by reaction of olefins with aluminum chloride. It also has a very high absorptive power for aluminum chloride itself, and acts to absorb aluminum chloride from the butane vapors. In case the olefins or other unsaturates from line 5 are added continuously to the stream of catalyst chamber effluents, these unsaturates may react with the

aluminum chloride vapors in the stream to form sludge and/or the aluminum chloride vapors may be absorbed from the stream by the sludge flowing over the packing in chamber 9, with the unsaturates reacting with the thus absorbed aluminum chloride to form additional amounts of an inactive sludge. Probably both such actions occur, the extent of each depending on, among other things, the length of time the unsaturates remain mixed with the aluminum chloride-bearing hydrocarbon gases before the sludge in chamber 9 is contacted. At any rate, the aluminum chloride becomes incorporated in the sludge, and reacts with added unsaturates to form sludge, and the hydrocarbons are freed of the residual aluminum chloride by such reaction.

The unsaturates may be added intermittently rather than continuously. It has been found that when this is done, the aluminum chloride-hydrocarbon sludge will readily absorb the aluminum chloride vapors even in the absence of the unsaturates. However, as the amount of free aluminum chloride dissolved in the sludge increases, the readiness with which additional aluminum chloride is dissolved is decreased. Thus after a period of operation the sludge becomes activated with free aluminum chloride to such an extent that not all of the aluminum chloride carried over by the effluent stream from the conversion zone is absorbed. When this happens, or before such condition is reached, the unsaturates are introduced to react with the aluminum chloride to ensure its complete removal from the hydrocarbons. Sufficient unsaturates are used for a sufficient length of time to ensure that the sludge is substantially spent or at least to ensure that the sludge is kept deactivated to or below a satisfactory value at all times. After sufficient unsaturates have been thus introduced, the system may again be operated for a period of time without the addition of unsaturates.

Depending upon conditions in chamber 9, heavy polymers or alkylate formed by reaction of the olefins alone or with isobutane, may separate out in chamber 9 as a liquid and be removed through line 1A or otherwise, or they may remain in the vapor state and pass out through line 21.

In case it is undesirable to add unsaturates to the isomerization effluents, the two chambers, 9 and 10, may be utilized. In such case the catalyst chamber effluents are passed through chamber 9 in the absence of added olefins until the amount of uncombined aluminum chloride in the sludge is so great that absorption is not taking place to the desired extent. At such time, the flow is switched to chamber 10, in which the absorption of aluminum chloride in sludge continues. Meanwhile, unsaturates are passed through chamber 9 to react with the absorbed aluminum chloride therein and place the sludge in condition for further effective absorption. When the sludge in chamber 10 loses its absorptive capacity to too great an extent, the flow of butane isomerization effluents is again returned to chamber 9 while unsaturates are passed through chamber 10.

In the first cycle of such an operation valve 23 in line 11 and valve 27 in line 21 are open, allowing reaction zone effluents from line 3 to flow through chamber 9, while valve 24 in line 12 and valve 28 in line 20 are closed to prevent such flow through chamber 10. Valve 26 in line 14 and valve 30 in line 31 are open, allowing unsaturates from line 5 to flow through chamber 10 to deactivate the sludge therein, while valve

25 in line 13 and valve 29 in line 22 are closed to prevent access of unsaturates to chamber 9. The flow of unsaturates through chamber 10 may be stopped by closing valves 26 and 30 before it is necessary to put chamber 10 back into service for treating isomerization zone effluents.

When the sludge in chamber 9 becomes too activated with absorbed uncombined aluminum chloride, valves 26 and 30 are closed if they are not already closed, valves 24 and 28 are opened to permit passage of material from conduit 3 through chamber 10, and valves 23 and 27 are closed to stop such passage through chamber 9. Unsaturates are then passed through chamber 9 via lines 13 and 22 by opening valves 25 and 29. Sludge is circulated through chamber 10 by means of conduits 16 and 18, and excess sludge is removed via conduit 1B. A certain amount of polymerization of the unsaturated hydrocarbons used in the deactivation step will occur, and if desired these polymerization products can be recovered from the unsaturated hydrocarbon effluent stream from the deactivation step or separated as liquids from the sludge in suitable manner.

The cycle described may be continued indefinitely, with one of the two chambers always being on-stream for absorption of aluminum chloride, while the other is being treated with unsaturates to sludge the free aluminum chloride therein, or is standing by ready for service. More than two chambers may be used for this type of operation if desired, as will be well understood by those skilled in the art.

The type of unsaturated hydrocarbons used in any particular modification of this invention will depend upon the availability of such unsaturated hydrocarbons and upon the nature of the saturated hydrocarbons being treated. Frequently the normally gaseous olefins are convenient to use, since their degree of unsaturation per unit of weight is high. I have also found that liquid olefins are useful in my process; for example, gaseous saturated hydrocarbons containing residual aluminum chloride may be bubbled through a body of heavy liquid olefinic polymers, which may be obtained as by-product from other hydrocarbon conversion processes. If desired, such heavy polymers may be recirculated with the sludge in packed chambers as described above. These and other modifications are within the scope of my invention, which is to be limited only by the appended claims.

I claim:

1. In a hydrocarbon conversion process utilizing a Friedel-Crafts type metal halide catalyst wherein effluent substantially saturated hydrocarbons contain residual metal halide, the method of freeing said effluent hydrocarbons from said metal halide which comprises contacting said effluent hydrocarbons with a metal halide-hydrocarbon sludge to effect removal of said metal halide by absorption in said sludge, stopping the contacting of said effluents with said sludge whenever the concentration of free metal halide in said sludge becomes sufficiently high to prevent the absorption of additional amounts of said metal halide from said effluents to a desired extent, contacting unsaturated hydrocarbons with said sludge until the concentration of free metal halide in said sludge is diminished to a desired extent, and again contacting said sludge with said effluents to effect absorption of metal halide therefrom.

2. A continuous process for the isomerization

of normal butane which comprises continuously passing an anhydrous gaseous mixture comprising a major proportion of normal butane admixed with a minor proportion of hydrogen chloride into contact with a solid anhydrous aluminum chloride catalyst at conditions of temperature, pressure, and contact time to give a substantial yield of isobutane, passing gases from said contacting into contact with a first increment of aluminum chloride-hydrocarbon sludge under conditions favoring absorption of aluminum chloride vapors from said gases by said sludge, recovering isobutane and recycling hydrogen chloride and unconverted normal butane to contact with said catalyst, periodically changing the flow of gases from contact with said first increment of said sludge into contact with a second increment of said sludge, contacting low-boiling monoolefins with said first increment of sludge to react with absorbed aluminum chloride therein, thus forming additional sludge, and then re-establishing the flow of gases into contact with said first increment of sludge to effect further absorption of said aluminum chloride vapors from said gases.

3. A process for conversion of low-boiling hydrocarbons with a Friedel-Crafts type metal halide catalyst, which comprises passing a stream of low-boiling hydrocarbons in contact with such catalyst under conditions to effect the desired conversion and whereby some metal halide becomes incorporated in said stream, passing the resulting stream in vapor phase in contact with a liquid metal halide-hydrocarbon sludge to absorb said metal halide from said stream, intermittently introducing into contact with said stream and said sludge an excess of a liquid olefinic polymer to react with said metal halide and to maintain the concentration of uncombined metal halide in said sludge at a low value conducive to allowing further absorption of metal halide from said stream, and recovering from said stream conversion products substantially free from metal halide.

4. In a hydrocarbon conversion process utilizing a Friedel-Crafts type metal halide catalyst wherein effluent substantially saturated hydrocarbons contain residual metal halide, the method of freeing said effluent hydrocarbons from said metal halide which comprises contacting said effluent hydrocarbons with a metal halide-hydrocarbon sludge to effect removal of said metal halide by absorption in said sludge, and whenever the concentration of free metal halide in said sludge becomes sufficiently high to prevent the absorption of additional amounts of said metal halide from said effluents to a desired extent, contacting unsaturated hydrocarbons with said sludge until the concentration of free metal halide in said sludge is diminished to a desired extent.

5. A process according to claim 4 in which said metal halide is an aluminum halide.

6. A process according to claim 4 in which said metal halide is aluminum chloride.

7. A process according to claim 4 in which said sludge is continuously circulated over an inert packing material thus presenting an extended surface of sludge to said hydrocarbons.

8. In a hydrocarbon conversion process utilizing a Friedel-Crafts type metal halide catalyst wherein effluent substantially saturated hydrocarbons contain residual metal halide, the method of freeing said effluent hydrocarbons from said metal halide which comprises contacting said ef-

fluent hydrocarbons with a metal halide-hydrocarbon sludge to effect removal of said metal halide by absorption in said sludge, and introducing unsaturated hydrocarbons into contact with said sludge to react with thus-absorbed metal halide, at least a part of said removal being accomplished in the absence of thus introduced unsaturated hydrocarbons.

9. A process according to claim 8 in which said conversion is an isomerization reaction.

10. A process according to claim 8 in which said conversion is an alkylation reaction.

11. A process according to claim 8 in which said unsaturated hydrocarbons are intermittently introduced into a zone wherein said effluent hydrocarbons are continuously contacting said sludge.

12. A method of removing uncombined Friedel-Crafts type metal halide from substantially saturated hydrocarbons containing the same, which comprises passing such hydrocarbons in the vapor phase in contact with a liquid metal halide-hydrocarbon sludge under conditions favoring absorption of said metal halide by said sludge, and maintaining the concentration of uncombined metal halide in said sludge below a value so high as to prevent absorption of said metal halide from said hydrocarbons to a desired extent, by reacting said metal halide with unsaturated hydrocarbons.

13. The method of claim 12 in which said saturated hydrocarbons are passed in the vapor phase through a chamber containing solid contact material in countercurrent contact with said sludge and with liquid olefinic polymers, and in which said sludge and said polymers are recirculated over said contact material in said chamber.

14. A process according to claim 12 in which said substantially saturated hydrocarbons comprise relatively low-boiling paraffins.

15. A process according to claim 12 in which said unsaturated hydrocarbons comprise olefins.

16. In the removal of Friedel-Crafts type metal halides from hydrocarbon vapors comprising essentially saturated hydrocarbons, the improvement which comprises passing such vapors containing such metal halide in contact with liquid olefinic polymers, thereby reacting said metal halide with said polymers to form a sludge, and separating from said polymers and said sludge the hydrocarbon vapors thus freed of said metal halide.

17. A continuous process for the conversion of hydrocarbons which comprises continuously passing a stream of hydrocarbon material to be converted through a catalyst zone containing a Friedel-Crafts type metal halide catalyst at conversion conditions, circulating separate increments of metal halide-hydrocarbon sludge through each of at least two contacting zones adapted to effect intimate contact between sludge and hydrocarbons, passing a stream of substantially saturated hydrocarbons obtained from said catalyst zone and containing residual metal halide through one of said contacting zones under conditions adapted to effect removal of said residual metal halide from said stream by absorption in said sludge, passing a stream of unsaturated hydrocarbons through another of said contacting zones under conditions adapted to effect reaction of said unsaturated hydrocarbons with free metal halide in said sludge, and periodically changing the flow of said stream of substantially saturated hydrocarbons and the flow of said stream of unsaturated hydrocarbons so that each of said contacting zones is alternately on-stream for said saturated hydrocarbons and on-stream for said unsaturated hydrocarbons.

KARL H. HACHMUTH.
